(57) **CLAIM**

The ornamental design for a solar wall light as shown and described.

DESCRIPTION

FIG. 1 is a front, top, right perspective view of a solar wall light showing my new design;

FIG. 2 is a front, bottom, right perspective view thereof;

FIG. 3 is a front view thereof;

FIG. 4 is an enlarged right view thereof;

FIG. 5 is an enlarged left view thereof;

FIG. 6 is a back view thereof;

FIG. 7 is a bottom view thereof;

FIG. 8 is a top view thereof; and,

FIG. 9 is an enlarged view of the encircled area 9 of FIG. 7. The dash-dash style broken lines shown in the drawings depict portions of the solar wall light that form no part of the claimed design. The dash-dot style broken lines illustrate the boundaries of the enlarged portion views shown in the drawings and form no part of the claimed design.
